G. W. SCHAUERTE

CARTRIDGE SHELL AND PROCESS OF MAKING THE SAME

Filed Oct. 6, 1923

UNITED STATES PATENT OFFICE.

GEORGE W. SCHAUERTE, OF ALTON, ILLINOIS, ASSIGNOR TO WESTERN CARTRIDGE COMPANY, OF EAST ALTON, ILLINOIS, A CORPORATION OF DELAWARE.

CARTRIDGE SHELL AND PROCESS OF MAKING THE SAME.

Application filed October 6, 1923. Serial No. 666,916.

To all whom it may concern:

Be it known that I, GEORGE W. SCHAUERTE, a citizen of the United States, and residing at Alton, county of Madison, 5 State of Illinois, have invented the new and useful Improvement in Cartridge Shells and Processes of Making the Same, of which the following is a specification.

This invention relates to cartridge shells, 10 and more particularly to those designed for use in shot guns.

A shot gun shell usually comprises a tube, 15 usually formed of paper or similar material, a base which is usually formed of metal, such as brass, and a base wad also usually formed of paper, the base and the base wad being provided with a socket for receiving a battery cup. It is necessary that the elements of the cartridge shell be 20 firmly interlocked to form a unitary structure.

One of the objects of this invention, therefore, is to provide a cartridge shell in which the base and the base wad will be 25 securely interlocked in a simple and effective manner.

Another object of this invention is to provide a cartridge shell embodying a tube of paper or the like, in which the base wad 30 will not only be interlocked with the base but also with the tube, while the tube itself will be interlocked with the base.

Another object of this invention is to provide a novel process of assembling the 35 elements of the cartridge shell, whereby these elements are interlocked in a simple and effective manner to form a unitary structure.

Further objects will appear from the detail description taken in connection with the accompanying drawing, in which:

Figure 1 is a detail section, somewhat enlarged, of the base end of the shell showing one of the steps in the interlocking of the 45 elements of the shell;

Figure 2 is a section showing the process of securing interlocking of the elements;

Figure 3 is a view similar to Figure 1 but in perspective showing the elements of 50 the shell interlocked; and

Figures 4, 5, 6 and 7 are sectional views showing various embodiments of this invention.

Referring to the accompanying drawing 55 and more particularly to Figures 1 and 3,

the elements of the shell comprise a tube 1, which is usually formed of paper, a base-wad 2, also usually formed of paper, and a base 3 which is drawn to shape and is usually formed of brass. The base and the base 60 wad are apertured to form a socket which is arranged to receive a battery cup 4 of any suitable or usual construction. The base also has the usual peripheral flange 5.

In accordance with this invention the 65 base flange 5 is preliminarily formed only partially as shown in Figure 1 so as to permit ready insertion of the tube 1. The center of this base is also formed to provide a central flange which is serrated to form a 70 series of prongs 6 and the ends of these prongs are turned to project outwardly as shown at 7. The base-wad furthermore has its aperture 8 large enough so as to slip freely over the battery cup and the outwardly projecting prongs 7 which, as heretofore described, provide an anchor. After the elements of the shell have been assembled, as shown in Figure 1, they are secured together in interlocking relation by a 75 process of condensing the base-wad and crimping the base flange 5 by upsetting the partially formed peripheral flange 5. These operations can be performed by any suitable mechanism. Thus, as shown in 80 Figure 2, the assembled elements may be placed inside of a tubular support 9 having an annular recess 10 to receive the flange 5, while insertible into the tube is a plunger 12 formed as shown and cooperating with a 85 second plunger 11. In operation the plunger 11 is moved towards the support 9 and against the base 3, while the plunger 120 is moved into the shell to act upon the base-wad. This will cause the base-wad to 90 be condensed and to close in on the battery cup and the anchor surrounding the same, and cause the anchor to become firmly imbedded in and interlocked with the base-wad. Furthermore the cooperation of the 100 plunger 11 with the plunger 120 not only causes the end of the tube to be forced into the annular recess formed by the incomplete flange 5, but the end of the base-wad itself will be forced out against the end of the tube; furthermore the pressing of the base against the shoulder 10 will complete the upsetting of the flange 5 and thus firmly crimp the base on the tube. The result 105 is, therefore, that the elements of the tube 110

will become firmly interlocked as shown in Figure 3 with the base-wad interlocked with the base and with the tube, while the tube is interlocked with the base.

5 In the embodiment shown in Figure 4 a reinforce 12 is provided for the base 3 and this reinforce has a central flange serrated to form prongs 60 provided with outturned ends 70 thereby forming anchors similar to 10 6 and 7 and lying against the battery cup 4. This reinforce is usually of steel and when used, the flange on the base need only be short as shown in Figure 4, while the anchor on the reinforce forms in effect a continuation 15 of this flange. In the assembling of the elements shown in the embodiment of Figure 4 it will be understood that both the base and the reinforce have their peripheral flanges 5 and 50 only partially formed in 20 a manner similar to that shown in Figure 1, and that in the interlocking of the parts the operation will be substantially as shown in Figure 4, namely the condensation of 25 interlocking engagement with the anchor on the reinforce, while the flanges 5 and 50 are upset so as to secure interlocking of the tube, reinforce and base.

In the embodiment shown in Figure 5, 30 anchors are formed both on the base 3 and on the reinforce 12. The construction and the process of interlocking the elements of the shell will be readily understood from what has been described with reference to 35 Figures 1 to 4 inclusive.

In the embodiment shown in Figure 6 the battery cup itself has the anchor formed thereon by upsetting its inner end to form a peripheral flange 71 which is arranged 40 to interlock with the base-wad, for it will be readily understood that upon condensation of the wad the same is forced against the battery cup and underneath the flange thereon so as to effectively interlock the 45 parts, it being understood that the battery cup itself is provided with a flange 13 which is retained by a socket formed by flanging inwardly the base shown at 14.

In the embodiment shown in Figure 7 the 50 battery cup 4 has struck up therefrom prongs 72 over which the base-wad 2 is arranged to be slipped to be subsequently condensed so as to imbed these prongs in the base-wad. In this embodiment also the 55 battery cup is retained by the engagement of the flange 13 thereon with the flange 14 on the base.

It will, therefore, be seen that the invention 60 accomplishes its objects. A cartridge shell is provided in which the elements thereof are secured in firm interlocking engagement in a simple and effective manner. The arrangement is such that the tube and the base-wad can be readily slipped into the 65 base and over the battery cup and the out-

wardly projecting anchors; then by a simple operation the wad is condensed on the battery cup and the anchor to interlock the same, while the base-wad, tube and base are firmly interlocked.

It is obvious that various changes may be made in details without departing from the spirit of this invention; it is, therefore, to be understood that this invention is not to be limited to the specific details shown and 75 described.

Having thus described the invention, what is claimed is:

1. A cartridge shell comprising, a base and a base wad provided with a primer 80 socket, and an anchor on said base and projecting outwardly from said socket, said wad being condensed into interlocking engagement with said anchor.

2. A cartridge shell comprising, a base provided with a central flange adapted to form a primer socket and an anchor, and a base wad interlocking with said anchor.

3. A cartridge shell comprising, a base provided with a central flange adapted to 90 form a primer socket and turned outwardly to form an anchor, and a base wad interlocking with said anchor.

4. A cartridge shell comprising, a base provided with a central flange adapted to 95 form a primer socket and turned outwardly to form an anchor, and a base wad condensed into interlocking engagement with said anchor.

5. A cartridge shell comprising, a base provided with a primer socket, a reinforce therefor provided with an anchor projecting outwardly from said socket, and a base 100 wad interlocking with said anchor.

6. A cartridge shell comprising, a base, a reinforce therefor provided with an anchor projecting outwardly from said socket, and a base wad condensed into interlocking engagement with said anchor.

7. A cartridge shell comprising, a base provided with a socket, a battery cup therein, an anchor projecting outwardly from 110 said cup, and a base wad interlocking with said anchor.

8. A cartridge shell comprising, a base provided with a socket, a battery cup therein, an anchor projecting outwardly from 115 said cup, and a base wad condensed to close around said cup and interlock with said anchor.

9. In the art of making cartridge shells, the process comprising, placing a base wad with the aperture therein loosely over an anchor on the base and condensing the wad to close around and into interlocking engagement with the anchor.

10. In the art of making cartridge shells, the process comprising, placing a base wad over a battery cup and an anchor on the base and condensing the wad to close on the cup 130

and into interlocking engagement with the anchor.

11. In the art of making cartridge shells, the process comprising, placing over a battery cup provided with an anchor, a base wad, with the aperture taking freely over the cup and anchor, and condensing the wad into interlocking engagement with the cup and anchor.
- 10 12. In the art of making cartridge shells, the process comprising, placing over a battery cup and an anchor on the base, a base wad with the aperture taking freely over the cup and anchor, and condensing the wad to close on the cup and into interlocking engagement with the anchor.

13. In the art of making cartridge shells, the process comprising, placing a tube in the base, placing the base wad with the aperture loosely over an anchor on the base, 20 condensing the tube on the anchor and interlocking the base with the tube.

14. In the art of making cartridge shells, the process comprising, placing a tube in the base, placing the base wad with the aperture loosely over an anchor on the base, and condensing the tube on the anchor while the base is crimped on the tube.

In testimony whereof I affix my signature this 14th day of Sept., 1923.

GEORGE W. SCHAUERTE.
